UNITED STATES PATENT OFFICE.

ARTHUR THOMAS COLLIER, OF ST. ALBANS, ENGLAND.

DIAPHRAGM FOR GRAMOPHONES, PHONOGRAPHS, TELEPHONES, AND THE LIKE.

1,385,243.

Specification of Letters Patent. Patented July 19, 1921.

Application filed September 26, 1919. Serial No. 326,622.

To all whom it may concern:

Be it known that I, ARTHUR THOMAS COLLIER, a subject of the King of Great Britain, residing at St. Albans, Hertfordshire, England, have invented new and useful Improvements in Diaphragms for Gramophones, Phonographs, Telephones, and the like, of which the following is a specification.

10 This invention relates to diaphragms for gramophones, phonographs, telephones, and the like of the kind comprising a flat apertured part of one material and a flat part of another material covering or closing this

15 aperture.

It has heretofore been proposed to provide a diaphragm with a cupped edge, and a ring movable relatively to the sound box frame and arranged to apply variable tension to the diaphragm.

According to this invention there is provided a diaphragm comprising an apertured part of one material and a part of another material covering or closing this 25 aperture, in combination with means for applying variable tension to the compound diaphragm. This tension is applied to all parts of the diaphragm being communicated to the part closing the aperture by the 30 surrounding apertured part.

This compound diaphragm is mounted on the sound box in a manner similar to that employed for mounting the parchments of drums, for example, by clamping the outer 35 edge of the diaphragm on to the frame or casing of the sound box by means of a split ring the ends of which are drawn together by screws, the said outer edge of the diaphragm being cupped for the purpose, or by 40 cementing or otherwise securing this cupped edge of the diaphragm to a ring mounted around or co-axially with the said frame or casing.

To subject the diaphragm to the requisite 45 tension a ring may be provided to press against the diaphragm adjacent to the edge of the sound box frame or casing, this ring being moved or adjusted by means of set screws, or the ring to which the diaphragm 50 is cemented or otherwise secured as above mentioned may itself be similarly adjustable relatively to the sound box frame or casing.

In the accompanying drawing I have 55 shown how the said invention may be con-

veniently and advantageously carried into practice. In this drawing:

Figure 1 is a front view and

Fig. 2 a central section of a diaphragm constructed according to this invention, 60 mounted on a sound box casing.

Fig. 3 is a front view of a diaphragm mounted on a sound box casing, illustrating a modified construction of diaphragm.

Figs. 4 and 5 are views similar to Fig. 2; 65 illustrating modifications of the method of stretching or obtaining the requisite tension in the diaphragm.

As shown in Figs. 1 and 2 *a* is a diaphragm part of a placid or supple sheet material which becomes sonorous when subjected to tension and which has a relatively low natural period of vibration, such as parchment, vellum, or thin celluloid, having an aperture therein which is covered or 70 closed by a diaphragm part *b* of mica, glass, natural ivory, or other more brittle or rigid material than that of the part *a* and having a relatively higher natural period of vibration. The edge of the aperture in the part 80 *a* is serrated or slit so as to provide tongues *c* which are alternately cemented to opposite sides of the part *b*. The two parts of the compound diaphragm are thus brought substantially into one plane. This method 85 of joining the adjacent edges of the parts of the diaphragm can be applied to the construction of diaphragms having more than two parts respectively made of the alternative materials mentioned above, or equivalents thereof. 90

The outer edge of the part *a* is cupped so as to fit around the outer cylindrical surface of the sound box frame *d* to which it is secured without the use of a cement or adhesive, by means of a clamping or split ring *e* provided with lugs *f* and a tightening screw *g*. The compound diaphragm can then be readily removed and replaced, as desired. In this arrangement the outer cylindrical 100 surface of the said frame *d* and the corresponding inner face of the ring, between which the parchment is clamped, may either of them, or both, be roughened, and if desired a small strip or plate *e'* of metal may 105 be inserted at the split part of the ring *e* to prevent puckering of the parchment as the ring is tightened to clamp it around the sound box frame *d*.

The lugs *f* may be formed with extensions 110

h suitably shaped to provide a support for the pivotal mounting of a stylus bar.

When the above described arrangement of clamping ring *e* is employed a stretching 5 ring *i* is arranged within the sound box frame in which it is adjustable by means of screws *j*. This ring *i* has an integral apertured back plate *k* so that, as the ring *i* is advanced out of the frame *d* to stretch the 10 diaphragm, the depth of the space immediately behind the diaphragm remains constant. A vulcanite, compressed fiber or like washer may be arranged under the points of the adjusting screws *j* to prevent jarring.

15 In Fig. 3 a modified construction of compound diaphragm is illustrated. In this case the mica part *b'* overlaps the parchment part *a'* and is secured thereto by a suitable adhesive. The edge of the mica 20 part is covered by a ring *m* of paper, tracing cloth, parchment or the like, also secured by a suitable adhesive such as fish glue, and instead of plain circular edges as shown these parts may be serrated or of other desired form to avoid a sharp line of demarcation between the different materials.

The cupped edges of the compound diaphragm, instead of being held beneath a clamping ring, may be cemented or otherwise fastened to a ring *n* as shown in Fig. 30 4, provided with set screws *j* by which the ring *n* is forced away from the sound box frame *d* in order to subject the diaphragm to tension and hold these parts together.

35 The diaphragm shown in Fig. 4 is similar in construction to that shown in Fig. 3. In the arrangement shown in Fig. 5, the sound box frame *d'* is provided with a cylindrical extension *o* supporting a ring *p* having a 40 conical surface *q* over which the cupped edge of the diaphragm is drawn and fastened. The ring *p* is adjusted by screws *j*. If desired, the edge of the frame *d* (or *d'*) over which the compound diaphragm is 45 drawn may be rounded or beaded or it may be covered or provided with a projecting india rubber or like ring against which the diaphragm is tightly drawn.

In the application of this invention to the diaphragm of a telephone receiver a 50 part of the compound diaphragm is made of ferrotype iron or other suitable magnetic material and in its application to a telephone transmitter the diaphragm comprises a carbon part. 55

By employing a compound diaphragm under tension as herein described a more exact recording and reproduction of sounds is obtained than when using a diaphragm of a single material since overtones or other 60 components of the sounds to which one material is unresponsive will be recorded and reproduced by a part of the diaphragm of another material.

I claim—

1. A sound recording or reproducing diaphragm comprising a flat apertured outer part of a supple material which is sonorous when stretched, and a flat inner part of a more rigid material closing the aperture in 70 the first-mentioned part and having its outer margin firmly connected to the margin around the said aperture.

2. A sound recording or reproducing diaphragm comprising a flat apertured outer 75 part of a supple material which is sonorous when stretched, a flat inner part of a more rigid material closing the aperture in the first-mentioned part, and a layer of adhesive material connecting a marginal portion of 80 the inner part to a marginal portion around the aperture in the outer part.

3. A sound recording or reproducing diaphragm comprising a flat apertured outer part of one material, a flat inner part of another material closing the aperture in the 85 first-mentioned part, a distinct ring of material covering the joint between the said inner and outer parts on one side of the diaphragm and a layer of adhesive material 90 securing the said ring to the said outer and inner parts.

ARTHUR THOMAS COLLIER.
